UNITED STATES PATENT OFFICE.

BENJAMIN F. GORSUCH, OF MARTINSBURG, PENNSYLVANIA, ASSIGNOR OF ONE-THIRD TO CRAWFORD BLACK, OF MARTINSBURG, PENNSYLVANIA.

DESIGN FOR A SHOE-NAIL.

46,669.

Specification for Design.

Patented Nov. 24, 1914.

Application filed August 24, 1914. Serial No. 858,333. Term of patent 14 years.

To all whom it may concern:

Be it known that I, BENJAMIN F. GORSUCH, a citizen of the United States, residing in Martinsburg, in the county of Blair and State of Pennsylvania, have invented a new, original, and ornamental Design for a Shoe-Nail, of which the following is a specification, reference being had to the accompanying drawing, forming part thereof.

In the drawings a single perspective figure discloses my ornamental design for a shoe nail.

I claim:—

The ornamental design for a shoe nail, as shown.

BENJAMIN ^{his} X F. GORSUCH.
mark.
